United States Patent Office.

ALBERT D. JUDD, OF NEW HAVEN, CONNECTICUT.

Design No. 4,000, dated April 26, 1870.

DESIGN FOR A DRAWER-PULL.

The Schedule referred to in these Letters Patent and making part of the same.

To all whom it may concern:

Be it known that I, ALBERT D. JUDD, of New Haven, in the State of Connecticut, have invented and made a new and original Design for the shape and configuration of a Drawer-Pull; and the following is hereby declared to be a correct description of the same.

In the drawing—

Figure 1 is a plan of the said pull;

Figure 2 is an elevation; and

Figure 3 is a cross-section.

The shape that is given to this drawer-pull is such as to be ornamental, and, at the same time, convenient for the fingers to pass behind the pull in opening the drawer.

The general shape of the front portion *a* of the pull

is that of a section of a hollow cone, the sides at *b b* being nearly straight but inclined, and *c c* are the ornamental ears for the screw-holes.

The top portion *d* of the pull is rounded.

The surface of the pull may be more or less ornamented with figures or designs, in relief, or sunken into the surface, such not forming any portion of my present invention.

I claim as my invention—

The design of the shape and configuration of the drawer-pull, as described and represented.

Signed by me this 17th day of March, 1870.

ALBERT D. JUDD.
